[57] CLAIM

The ornamental design for a stuffing tube for passing electrical current through bulkheads, as shown and described.

DESCRIPTION

FIG. 1 is a side elevational view of a stuffing tube for passing electrical current through bulkheads showing my new design;

FIG. 2 is a left end view thereof;

FIG. 3 is a right end view thereof;

FIG. 4 is a top plan view thereof;

FIG. 5 is a right end perspective view thereof;

FIG. 6 is a left end perspective view thereof; and

FIG. 7 is a sectional view thereof.

FIG. 1
